LOCK FOR DOORS

Rudolf Grill, New York, N. Y.

Application June 26, 1934, Serial No. 732,525

2 Claims. (Cl. 292—173)

This invention relates to locks and particularly to an improved lock for doors, the object being to provide a construction which will properly lock a door closed and at the same time present means 5 for permitting the ready opening thereof whenever desired.

Another object of the present invention is to provide an improved lock which is especially useful on ice boxes or refrigerators of some appreciable size, the structure presenting means whereby the door may be forced open even though frozen to a greater or lesser extent.

An additional object of the invention is to provide an improved lock for refrigerators and the like wherein the lock may be opened either from the outside or the inside of the door.

A still further object, more specifically, is to provide an improved lock for ice boxes, refrigerators and the like wherein the lever used for withdrawing the bolt of the lock also acts as a lever in connection with the keeper for prizing or forcing the door partly open, thus breaking any ice seal which may have formed.

In the accompanying drawing—

Figure 1 is a horizontal sectional view through part of a large refrigerator, with a lock embodying the invention applied thereto;

Figure 2 is a sectional view through Figure 1 approximately on the line 2—2;

Figure 3 is a transverse sectional view through Figure 1 on the line 3—3.

Referring to the accompanying drawing by numeral, 1 indicates a refrigerator as a whole, and 2 the door, which may be of any desired construction. A lock 3 is provided for locking the door closed and also for providing a handle whereby the door may be opened. While the device has been shown in the embodiment applied to a refrigerator, it will be understood that it may be used in connection with any kind of doors, particularly heavy doors. The lock as illustrated is provided with a keeper 4 which has a base 5 held in place by suitable screws 6 which have their heads exposed at all times. The base 5 is formed with an externally threaded bore 7, and in the bottom of this bore there is positioned a screw 8 which is hidden and which cannot be reached without removing the keeper head 9, which head is provided with a shank 10 screwed into the threaded bore 7. A set screw 11 is provided for locking the threaded shank 10 against movement. It will be observed that this set screw is arranged adjacent the end of the bolt 12, and consequently cannot be reached by anyone until the bolt 12 has been withdrawn and the door swung open. It

will be noted that the head 9 is provided with an under surface 13 against which the bolt 12 reacts when in locked position. The surface 13 merges into a curved end 14, which in turn merges into a rounded surface 15 rather sharply which acts as a fulcrum for the end 16 of the handle or hand lever 17. The lever 17 is pivotally mounted by the pin 18 on the lock casing 19 and is firmly connected to the pin by a suitable set screw 20. This lever has a grip 21 at the end opposite the end 16. Near the pin 18 the lever 17 is provided with an extending finger 22 which fits into the socket 23 formed in the bolt 12, whereby the finger 22 may act against the wall or abutment 24 to move the bolt 12 to an unlocked position, said movement being against the action of the spring 25. Bolt 12, spring 25 and associated parts are arranged in a recess 26 in the base 27, said base having its side parts merging into the flanges of casing 19. It will be noted from Fig. 1 that part of the lever 17 passes between these flanges and the abutment 28 and strikes the base 27 near the rear thereof. When the lever is open or in substantially the dotted position shown in Fig. 1, a flat spring 29 closes the opening in the casing 19, said spring being slightly narrower than the opening in the casing and at one end being provided with an enlargement 30 which has an aperture whereby it may fit over the extension 31 of base 27. The spring 25 also fits over this extension and over a suitable extension 32 of the bolt 12. Extension 32 is divided centrally so that the cable 33 may be connected to the pin 32' and then extend through the hollow extension 31, through the passageway 34 in base 27 and passageway 35 in door 2. A ring or other object 36 is secured to the cable at the end projecting to the inner surface of the door 2 whereby anyone within the ice box or refrigerator may pull on ring 36 and withdraw the bolt 12 so that the door may be opened. This will prevent a person from being confined within the refrigerator provided that a lock embodying this invention is provided on the door thereof. While anyone may freely open the lock from inside, it cannot be freely opened from the outside if a bolt or padlock is passed through the aperture 37 and the padlock moved to locked position, as this will prevent the lever 17 from swinging outwardly. The padlock coating with the aperture 37 and associated parts will prevent anyone on the exterior of the icebox from opening the same, but will not prevent anyone from opening the door from the inside as the bolt will slide freely notwithstanding the function of the padlock.

When the parts are in the position shown in 55

Fig. 1 the bolt 12 is in locked position and the door 2 is held closed. If it should be desired to open the door the grip 21 is grasped by hand and pulled downwardly to the dotted position shown in Fig. 1 and then further downwardly until the door is opened. When moved to the position shown in Fig. 1 the bolt 12 is retracted until it is free of the lever 4. Quite often in refrigerators moisture gathers around the door and freezes 10 and prevents the ready opening of the door. If this occurs the lever in moving to the dotted position shown in Fig. 1 will retract the bolt, 12, and then the end 16 of the lever will press against the rounded surface 15 of keeper 4 and by this 15 leverage or fulcrum action will produce a great pull on the door and break the ice seal, notwithstanding the fact that the operator is exerting small force on the lever 17. After the door has started to open by reason of this great leverage, a further pull on the lever will cause the door to 20 swing open in the usual manner. As the bolt 12 is a spring pressed structure the door 2 may be slammed shut and this bolt will slide over the surface 15 being automatically retracted until it 25 passes the head 9, whereupon the spring 25 will cause the bolt to snap into locked position. Spring 25 by forcing the bolt to its locked position will cause the wall or abutment 24 to engage the finger 22 and swing the same so that the lever 17 will be moved to its closed position, namely, the 30 position shown in Fig. 1 when the door has been completely closed. This is done even if the lever is not engaged by the hand.

In reference to the keeper it will be observed that the keeper head 9 is screwed into place and then locked by the screw 11. Whenever desired the screw 11 may be loosened and the keeper head 35

entirely removed, or the keeper head may be unscrewed partly so as to secure the desired offset and then the screw 11 reapplied.

I claim:

1. A lock for refrigerators comprising a base having a channel therein extending from one end toward the opposite end but falling short of said opposite end, a bolt slidably mounted on said channel and adapted to project from said base when in functioning position, a spring arranged within said channel and continually acting on said bolt for tending to move the same toward a functioning position, a pivotally mounted lever provided with a finger positioned to engage part of the bolt and retract the bolt when the lever is moved a predetermined distance around the pivotal point, means for receiving a padlock for locking the lever against functioning, and means extending from a point interior of the refrigerator for causing a withdrawal of said bolt, said means when actuated causing said bolt to be withdrawn regardless of the functioning of said padlock. 5 10 15 20 25

2. A lock for refrigerators and the like including a locking mechanism for locking the door of the refrigerator, said door having an inclined passageway therethrough, said locking mechanism having a base provided with a slideway, a sliding bolt slidably mounted in said slideway, a spring acting to move the bolt in one direction, a lever for moving the bolt in the opposite direction, 30 and a cable connected to said bolt and extending through the passageway in said door for permitting a person interiorly of the refrigerator to retract said bolt without disturbing the position of said lever. 35

RUDOLF GRILL.
